UNITED STATES PATENT OFFICE.

LADBROOK H. FREEMAN, OF CLEVELAND, OHIO, ASSIGNOR TO THE GUGGENHEIM LAUNDRY MACHINERY COMPANY, OF CLEVELAND, OHIO, A CORPORATION OF OHIO.

IRONING-PRESS.

1,220,619.

Specification of Letters Patent. Patented Mar. 27, 1917.

Application filed July 5, 1912. Serial No. 707,887.

To all whom it may concern:

Be it known that I, LADBROOK H. FREEMAN, a citizen of the United States, residing at Cleveland, in the county of Cuyahoga and State of Ohio, have invented certain new and useful Improvements in Ironing-Presses, of which the following is a specification.

This invention relates to laundry machinery generally and particularly to shirt and waist presses.

More specifically the invention relates to means for ironing the entire shirt bosom and the portions of the yoke lying between the rear curved corners of the neck band and the folding line.

The invention may be further briefly summarized as consisting in the construction and combination of parts hereinafter set forth in the following description, drawings and claims.

Referring to the drawings, Figure 1 is a side elevation of a portion of the machine provided with my invention; Fig. 2 is an enlarged detail view of the device applied to parts of the mechanism; Fig. 3 is a top plan view of the device showing the neck band former; Fig. 4 is a side elevation of the device looking to the right in the direction of the line 4—4 of Fig. 3; and Fig. 5 is a section upon the line 5—5 of Fig. 3.

In carrying out the invention any preferred form and construction of parts may be employed so long as they possess the necessary characteristics, but I have shown one form and construction in the drawings, which is highly effective in operation, and in such embodiment 1 represents the frame provided with an ironing board 2 having formed integral therewith a yoke ironer member 3 having a yoke ironer plate 4 mounted thereon with a portion 5 extending up above the surface of the board and back of the neck band former to be described. The frame is also provided with suitable brackets 6 having sockets 7 for receiving the movable ironing member to be later described. Secured to the ironing board is a neck band forming mechanism which may be of any preferred form except that it must comprise a main body portion 8 with a curved front edge and backwardly diverging sides as well as movable foot portions 9 which are mounted on slides 55 adapted to operate in a diagonal direction

in and out from the main body portion 8. The mechanism for performing the movement of these foot portions does not constitute any part of the invention and it is thought to be unnecessary that they should be described. The diagonal movement of the foot portions causes their outer side edges to move in the plane of the extreme sides of the main body portion, or in other words to enlarge the size of the neck band former without affecting its general shape.

The frame is also provided with a suitable bed 11 supporting a movable yoke ironer 12 adapted to be moved into and out of engagement with the yoke ironing plate 4 by any suitable mechanism, not shown. Secured to the side of this bed and on each side of the machine are suitable bearing blocks 13 which support movable arms 14 provided with bearing portions 15 for receiving rods 16 pivoted at their upper ends to brackets 17 both firmly secured to the ironing plate 18. This ironing plate conforms to the general configuration of the ironing board and has a recess 19 at the end 80 near the brackets 17 curved toward the body of the plate to conform to the curve of the body portion of the neck band former 8 and having diverging side edges in parallel alignment with the side portions of the body 85 portion of the neck band former.

The mechanism thus far described represents the type of machine to which the invention is applied and the description will now be confined to the mechanism which forms the subject of this invention.

One of the devices is secured to each inner corner of the ironing plate at the straight side edges of the recess 19, and a description of one will suffice for both.

This mechanism comprises a plate member 20 secured upon the upper surface of the ironing plate in any suitable manner, and having along the edge adjacent to the straight edge of the recess 19 an upwardly 100 extending guide 21 having an undercut edge 22 and a straight edge on the opposite side flush with the straight edge of the ironing plate at the recess 19. Slidably mounted on this guide 21 is an ironing member 23 having a recess 24 for receiving the guide 21 and extending over and under the undercut portion 22 so as to be held upon the guide. This member has a curved face 25 which conforms to the configuration of the 110

foot portions 9 of the neck band former. This member 23 has an upwardly extending pin 26 adapted to be engaged by a lug 27 carried by the movable ironing chest 28 which is supported in the sockets 7 of the brackets 6.

In utilizing the mechanism described, the operator places the shirt upon the bosom board with the neck band fastened with a 10 stud and adjusts the neck band former to the neck band in the usual way, the forward curved portion 8 of the neck band former moving down the board, and the rear portions 9 moving outward to fill the 15 neck band. The yoke ironer is then moved in place to iron the yoke and establish the folding line in alinement with the rear curved foot portions of the neck band former. The ironing plate is then lowered 20 upon the work and the ironing members 23 are moved inward so that their curved faces 25 engage the outside of the neck band at the foot portions 9, the under surfaces of these members lying over the portions of 25 the yoke arranged between the curved rear corners of the neck band and the folding line. The ironing chest is then lowered upon the work so that it engages the ironing plate. At the same time the lugs 27 project inward from the side walls of the neck 30 band recess, engage upon the tops of the pins 26 and force the corner ironing devices down upon the portions of the yoke below them. In this way the entire bosom, the 35 side portions of the yoke, and the corners between the back corners of the neck band and the folding line are ironed throughout.

In ironing shirts with the neck band formed in substantially a circular arrangement there is a folding line established and this folding line touches the neck band at the back, the curve of the neck band forming with this folding line angularly shaped portions which are normally left untouched 45 by any of the ironing machines employing the U-shaped or V-shaped recess in the ironing chest. This device is designed for completely ironing the entire exposed bosom and yoke portion to the folding line.

50 Having described my invention, I claim:—

1. In an ironing press, an ironing board, an ironing chest coöperating therewith, a neck band former arranged upon the board 55 and having the rear portion of its periphery in alinement with the end of the board, means for pressing the yoke to form a folding line at the end of the board, and means for ironing the complete bosom and the 60 portions of the yoke adjacent to the neck band to the folding line.

2. In an ironing press, an ironing board, an ironing chest coöperating therewith, a neck band former arranged upon the board 65 and having the rear portion of its periphery

in alinement with the end of the board, means for pressing the yoke to form a folding line at the end of the board, and means for ironing the portions of the yoke which lie between the curved back portion of the 70 neck band former and the folding line.

3. In an ironing press, an ironing board, a neck band former mounted thereon and adapted to conform to the natural configuration of the neck band, an ironing chest coöperating with the ironing board and having a recess therein having the curved forward edge and diverging side edges, means for establishing a folding line coincident with the back of the neck band, and means 75 for ironing the angular portions of the yoke lying between the diverging edges of the recess of the chest, the folding line and the neck band.

4. In an ironing press, an ironing board, 80 an ironing plate, an ironing chest, a neck band former, means for adjusting the neck band former to various sizes of neck bands, and means for ironing the back side yoke 85 portions of a shirt, said portions lying adjacent to the back outer corners of the neck band.

5. In an ironing press, an ironing board, an ironing plate, an ironing chest, a neck band former, means for adjusting the neck 90 band former to various sizes of neck bands, and adjustable side yoke ironers for ironing the back side yoke portions of a shirt, said portions lying adjacent to the back outer 95 corners of the neck band.

6. In an ironing press, an ironing board, an ironing plate, an ironing chest, a neck band former, means for adjusting the neck band former to various sizes of neck bands, and side yoke ironers mounted on the ironing 100 plate for ironing the back side yoke portions of a shirt, said portions lying adjacent to the back outer corners of the neck band.

7. In an ironing press, an ironing board, an ironing plate, an ironing chest, a neck band former, means for adjusting the neck band former to various sizes of neck bands, and adjustable side yoke ironers mounted on the ironing plate for ironing the back side yoke portions of a shirt, said portions 110 lying adjacent to the back outer corners of the neck band.

8. In an ironing press, an ironing board, an ironing plate, an ironing chest, a neck band former, means for adjusting the neck band former to various sizes of neck bands, guides mounted on the ironing plate, and side yoke ironers slidably mounted on said 115 guides.

9. In an ironing press, an ironing board, a neck band former mounted thereon, means for adjusting the rear back corners of the neck band former to fit any neck band, an ironing plate having a recess therein for 120

receiving the neck band former, an ironing chest coöperating with said ironing plate and said ironing board, and side yoke ironers mounted on the edge of said plate 5 adjacent to the recess which receives the neck band former and adjustable with respect to the rear and back corners of the neck band.

10. In an ironing press, an ironing board, a neck band former mounted thereon, means for adjusting the rear back corners of the neck band former to fit any neck band, an ironing plate having a recess therein for re-

ceiving the neck band former, an ironing chest coöperating with said ironing plate and said ironing board, and side yoke ironers slidably mounted on the edges of said ironing plate adjacent to the recess which receives the neck band former.

In testimony whereof I affix my signature 20 in presence of two witnesses.
